His Attorney.

UNITED STATES PATENT OFFICE.

ROMANO SERAFIN, OF HARTFORD, CONNECTICUT.

DESIGN FOR A POWER-STICK CLAMP FOR LOOMS.

59,380.

Specification for Design.

Patented Oct. 11, 1921.

Application filed March 30, 1920. Serial No. 370,014. Term of patent 3½ years.

To all whom it may concern:

Be it known that I, ROMANO SERAFIN, a citizen of the United States, and a resident of Hartford, in the county of Hartford, State of Connecticut, have invented a new, original, and ornamental Design for a Power Stick Clamp for Looms, of which the following is a specification, reference being had in the accompanying drawing, forming part thereof.

In the drawing—

The figure is a perspective view of the clamp showing my new design.

I claim:—

The ornamental design for a power stick clamp for looms, as shown.

ROMANO SERAFIN.
